By

UNITED STATES PATENT OFFICE.

JESSE W. WESTERDALE, OF GAYLORD, KANSAS.

DESIGN FOR A CORNER-PIECE AND PHOTOGRAPHIC DISPLAY-CABINET.

45,578.

Specification for Design.

Patented Apr. 7, 1914.

Application filed January 7, 1914. Serial No. 810,877. Term of patent 3½ years.

To all whom it may concern:

Be it known that I, JESSE W. WESTERDALE, a citizen of the United States, residing at Gaylord, in the county of Smith and State of Kansas, have invented a new, original, and ornamental Design for a Corner-Piece and Photographic Display-Cabinet, of which the following is a specification, reference being had to the accompanying drawing, forming part thereof.

The figure is a perspective view of my new design.

I claim:

The ornamental design for a corner-piece and photographic display cabinet substantially as shown.

JESSE W. WESTERDALE.

Witnesses:

PETER LUND,
E. A. LUND.
